UNITED STATES PATENT OFFICE.

CHARLES EDWARD NARY, OF GEORGETOWN, INDIANA.

SANITARY MILK-PROTECTOR.

1,114,632.

Specification of Letters Patent. Patented Oct. 20, 1914.

Application filed December 11, 1913. Serial No. 805,947.

To all whom it may concern:

Be it known that I, CHARLES E. NARY, a citizen of the United States, and a resident of Georgetown, in the county of Floyd and State of Indiana, have made certain new and useful Improvements in Sanitary Milk-Protectors, of which the following is a specification.

My invention is an improvement in sanitary milk protectors, and has for its object to provide a device of the character specified, for connection with a cow, and so arranged that it may be supported inclosing the udder of the cow, in such manner as to protect the udder from contact with foreign matters, and wherein mechanism is provided for supporting the device in the manner specified.

In the drawings: Figure 1 is a side view of the improved protector, in place on a cow, and, Fig. 2 is a perspective view of the protector detached.

In the present embodiment of the invention a sack is provided, of suitable material, as for instance of rubberized cloth, and water proofed, the said sack comprising a body portion 1, and extensions 2, 3 and 4. The body is of sufficient size to inclose and hold the udder of the cow, with the upper front edge of the bag, that is that portion 4^a of the edge between the extensions 2 and 3 in contact with the belly of the cow. The extension 4 is designed to be passed rearwardly between the rear legs of the cow, and tabs 5 and 5^a are connected with the extension 4. Other tabs 6 and 7 are connected with the extensions 2 and 3, and each tab 5—5^a—6 and 7 has its free end engaged with a metallic loop 8, each loop having an eye 9.

The tabs are of any suitable material, as for instance of leather, cloth, or of the same material as the bag, and each tab is secured at one end to the extension, by stitching or the like. The other end of each tab may be connected with the loop in any suitable manner, as for instance by stitching or rivets.

A strap 10 is arranged between the tabs of the extensions 2 and 3, the ends of the strap being passed through metallic loops 11, and then doubled back upon the body of the strap, and connected thereto by buckles 12 or the like. Straps 13 and 13^a are secured at one end to the strap 10 at each side of the center thereof, and the said straps pass rearwardly across each other adjacent

to the strap 10, to a connection with one of the tabs 15^a of the extension 4. The rear ends of the straps 13 and 13^a are passed through metallic loops 14, and are then doubled back upon the body of the strap and connected thereto by buckles 15. Each of the loops 11 and 14 is provided with a snap hook, and the snap hooks engage the eyes 9 of the loops 8 of the adjacent tabs.

The snap hook of the strap 13 is engaged with the eye of the tab 5, and the snap hook of the strap 13^a is engaged with the eye of the tab 5^a. A strap 15 is secured at its rear end to the strap 10 at its center, and between the connection of the straps 13 and 13^a in any suitable manner, as for instance by stitching, and the front end of the said strap 15 is passed forwardly through a ring 16, and is then doubled back upon the body of the strap and connected thereto by means of a buckle 17. Another strap 18 has its ends connected with the ring 16, the strap 15 being adapted to lie along the back of the cow, while the strap 18 is adapted to encircle the neck of the animal, as shown in Fig. 1. The ends of the strap 18 are passed through loops 19 having snap hooks 20, and the said ends are then doubled back upon the body of the strap and connected thereto by 85 buckles 21. The snap hooks 20 are engaged with the ring 16. The strap 10 lies transversely of the animal's back, just in front of the hip bones, and the straps 13 and 13^a cross each other on the animal's back just in rear 90 of the strap 10. Each strap then passes rearwardly and downwardly to its connection with the adjacent tab. The sack 1 is thus supported directly beneath the udder of the cow, the udder lying within the bag, 95 in such manner that no part thereof may contact with foreign substances.

The improved protector is designed to be worn while the animal is in the stall or grazing in the field, and may be left in place 100 except during the milking of the animal.

It will be understood that the protector is so held that it incloses the udder completely, the free edges of the sack contacting with the body of the cow, in such manner that nothing can touch the udder. The sack will be in practice made in different sizes, to suit the cow, and it will be understood that any desired means may be used for connecting the straps to the sack. Preferably the connection is detachable, and easily so, in order that the device may be

removed and replaced with but slight trouble. Preferably the tabs 5—5^a—6—7 are of webbing, of sufficient strength to retain the sack in place. The straps 10—5 13—13^a—18 may also be of webbing, or of any other suitable material.

I claim:

In a device of the character specified, a sack adapted to be arranged beneath the 10 udder of a cow, and a harness for holding the sack in position, and comprising a strap adapted to extend longitudinally of the back of the cow from the neck to approximately the hip bones, a collar for encircling the 15 neck of a cow and permanently connected to the front end of the first-named strap at one

end of the collar and detachably connected at the other end, a cross strap connected intermediate its ends to the rear end of the first-named strap, a pair of straps connected 20 with the last-named strap on opposite sides of the connection of the first-named strap and adapted to cross each other over the hip bones of the cow, the ends of the cross strap and the free ends of the last-named straps 25 having snap hooks, and the sack having means for engagement by the snap hooks to support the sack.

CHARLES EDWARD NARY.
